UNITED STATES PATENT OFFICE.

CHARLES W. VALENTINE AND ALFRED F. HELIN, OF WATERTOWN, NEW YORK, AS
SIGNORS TO THE BAGLEY AND SEWALL COMPANY, OF WATERTOWN, NEW YORK,
A CORPORATION OF NEW YORK.

PAPER-MAKING MACHINE.

Application filed November 8, 1927. Serial No. 231,830.

This invention relates to certain improvements in paper making machines of that class in which the web is formed on a making wire, such as a Fourdrinier machine.

5 In this class of machines, there is employed an endless forming wire which passes over a series of suction devices provided with perforations, the suction devices acting to remove water from the web during the process of its formation as the wire and web travel over these suction devices. These suction devices are generally in the form of boxes, the tops of which are usually of wood over which the wire slides, and the action 10 of the suction boxes tends to draw the wire down against the tops of the boxes, so that the mesh of the wire tends to groove the tops of the boxes, thus increasing frictional resistance and causing trouble in actuating 15 the forming wire.

It is the special object of the present invention to provide means for causing the suction boxes to change their positions relatively to the wire so that the wire will wear 20 these boxes uniformly and prevent the undesirable grooving above referred to.

A further object of the invention is to produce such a construction which shall be of simple form and which may accomplish 25 its purpose without sacrificing any rigidity of the mechanism or preventing the mechanism from suitably functioning.

With these and other objects not specifically referred to in view, the invention consists in certain novel parts, arrangements 35 and combinations which will be described in connection with the accompanying drawings and the novel features pointed out in the claims hereunto appended.

40 Generally speaking, the invention will include means for supporting the suction boxes so that they may be moved relatively to the making wire, this movement being such that the supports for the suction boxes 45 are reciprocated in opposite direction, thus causing a continuous angular variation of the boxes with relation to the wire, together with means whereby the boxes may be given a slight sidewise or widthwise movement 50 with respect to the making wire, such movement effecting a uniform wear of the boxes and an effectual preventing of the undesirable grooving.

A preferred construction for effecting the

objects of the invention is shown in the accompanying drawings, in which

Figures 1 and 2 are side elevations of a Fourdrinier machine of the usual type;

Figure 3 is a plan view of the suction box arrangement of the machine showing the making wire;

Figure 4 is a view showing the position of the boxes at the end of their movement in one direction;

Figure 5 is a similar view showing the position of the suction boxes at the end of their movement in the opposite direction, and

Figures 6 and 7 are plan and side views, respectively, of certain details of construction in the mounting of the suction boxes.

Referring now to these drawings in detail, 1 indicates the breast roll of a Fourdrinier machine, 2 the making or forming wire, and 3 the table rolls, these parts being supported in suitable framing 3', 4. The suction boxes, four of which are shown, are indicated at 5; 6 indicates the guide roll, and 7 the couch roll, the wire returning to the breast roll over suitable carrying rolls 8, 80 this construction being common in Fourdrinier machines.

These suction boxes extend across the machine, as shown, and in accordance with the invention means are provided for mounting these suction boxes so that they may be given an angular reciprocating movement and so that they may be given an endwise or widthwise movement relatively to the wire, this latter movement preferably being simultaneous with the angular movement. While the particular construction for effecting this may be somewhat varied, in the particular construction illustrated there is provided side framing 9, 10, on which is supported a pair of sliding frames 11, 12. Supported on these sliding frames, at each side, are standards 13, 14 and 15, which support top bars 17, to which the suction boxes 5 are secured in any suitable manner, as by hanger bolts 18, these being shown in detail in Figures 5 and 6. As there shown, the hanger bolts pass through plates 19 on the top bars 17, these plates being pivoted on pivots 20, slots 21 being provided in the plates so that the bolts may have a swinging movement in these slots for purposes hereinafter referred

These frames 11, 12 have a sliding movement on the side frames 9, 10, before referred to, and means are provided for reciprocating these frames in opposite directions so as to effect an angular movement of the suction boxes with respect to the wire, the angle of this movement constantly changing, and means are provided for reversing the direction of the movement, this being done automatically. While various constructions may be employed for effecting this movement, in the particular construction shown this movement is effected and at the same time limited by means of a screw rod 22 acting through a screw block or nut 23 suitably secured to the under side of the sliding frames 11, 12; before referred to, it being understood that this construction is duplicated on each side of the machine. The screw rod 22 on one side of the machine has a right hand thread and on the other side of the machine has a left hand thread. Therefore, by manipulating these screw rods the slides 11, 12 are moved in opposite directions. As shown, these screw rods are operated by a cross shaft 24, which is driven from a reversing motor 25 through suitable speed reducing gears, indicated at 26 in Figure 3. The drive from the shaft 24 to the screw rods 22 may be of any suitable character, this being illustrated as by means of belts 27 passing over pulleys 28 and pulleys 29 on each side of the machine, these last pulleys being mounted on a worm shaft 30, the worm 30 of which meshes with a worm wheel 31 on the outer end of the screw rod, this construction being duplicated on each side of the machine.

Means are provided for automatically reversing the motor to reciprocate the frames in opposite directions, such means including a reversing switch 32, which is operated through a crank 33 and a rod 34 by stops 35 carried on one of the sliding frames, as the frame 11.

With the construction so far described, it will be observed that the boxes are given an angular movement relatively to the wire, and the angle of this movement is constantly changing. While this gives good results, in the best practice of the invention means will also be provided for giving the boxes an additional sidewise or widthwise movement relatively to the wire, this movement preferably being simultaneous with the movement by which the angular variation in the position of the boxes is effected. While this may be accomplished in various ways, in the particular construction shown there are provided two sets of keys or splines 36, 37 and 38, 39 secured on the main frames 9, 10, these keys riding in grooves or slots formed on the under side of the sliding frames 11, 12. It will be observed that these keys are angularly arranged, the keys

36, 37 pointing inwardly and the keys 38, 39, on the opposite side of the machine, also pointing inwardly. With this construction, as the frames reciprocate, the angularity of the keys and slots effects a limited sidewise or widthwise movement of the frames, this movement occurring during the reciprocating or endwise movement heretofore described. With this combination of movements, a uniform wear of the suction boxes is effected and the objectionable grooving of the tops of these boxes is effectually eliminated.

The suction boxes are connected to a main suction pipe 40 by means of flexible connections 41, these connections permitting the various movements above referred to.

While the invention has been shown and described in its preferred forms, it will be understood that certain variations may be made in the form and arrangement of the parts and the specific means described for effecting the desired movement of the boxes without departing from the invention as defined in the appended claims.

What is claimed is:

1. In a paper making machine, the combination of a making wire, suction devices over which the wire passes, and means for giving the suction devices at each end an angular and a reciprocating movement relatively to the wire.

2. In a paper making machine, the combination of a making wire, suction devices over which the wire passes; means for giving the suction devices an angular movement relatively to the wire, and means for giving the suction devices an endwise movement relatively to the wire.

3. In a paper making machine, the combination of a making wire, suction devices over which the wire passes, means for giving the suction devices an angular and a reciprocating movement relatively to the wire, and means for giving the suction devices an endwise movement relatively to the wire.

4. In a paper making machine, the combination of a making wire, suction devices over which the wire passes, means for giving the devices a simultaneous sliding and swinging movement, and means for giving the devices an endwise movement.

5. In a paper making machine, the combination of a making wire, framing, slides supported by the framing, suction devices supported in the slides, and means for operating the slides angularly in opposite directions.

6. In a paper making machine, the combination of a making wire, framing, slides supported by the framing, suction devices supported in the slides, means for operating the slides in opposite directions, and means for giving the slides a sidewise movement.

7. In a paper making machine, the combination of a making wire, framing, slides supported by the framing, suction devices supported in the slides, means for reciprocating the slides in opposite directions, and means for effecting a sidewise movement of the slides as the slides reciprocate. 60
8. In a paper making machine, the combination of the making wire, framing, a pair of slides supported by the framing, suction boxes supported by the slides, a reversing motor, connections between the motor and slides for reciprocating the slides in opposite directions, and means for effecting a sidewise movement of the slides. 65
9. In a paper making machine, the combination of the making wire, framing, a pair of slides supported by the framing, suction boxes supported by the slides, a prime mover, connections from the prime mover for reciprocating the slides in opposite directions, means for reversing the prime mover, and means for effecting a sidewise movement of the slides. 70
10. In a paper making machine, the combination of the making wire, framing, a pair of slides supported by the framing, suction boxes supported by the slides, a prime mover for reciprocating the slides in opposite directions, means for reversing the prime mover, and means for effecting a sidewise movement of the slides as they reciprocate. 75
11. In a paper making machine, the combination of the making wire, a pair of sliding frames, suction boxes supported in the frames, an operating shaft, a right hand screw connected to one frame, a left hand screw connected to the other frame, connections to the screws from the shaft, a prime mover, and means for reversing the prime mover. 80
12. In a paper making machine, the combination of the making wire, a pair of sliding frames, suction boxes supported in the frames, an operating shaft, connections from the shaft for sliding the frames in opposite directions, a reversing motor, a reversing switch, and means for operating the switch from one of the frames. 85
13. In a paper making machine, the combination of the making wire, a pair of sliding frames, suction boxes supported in the frames, means for reciprocating the frames in opposite directions, and cooperating keys and grooves for effecting a sidewise movement of the frames. 90
14. In a paper making machine, the combination of the making wire, a pair of sliding frames, suction boxes supported by the frames, means for sliding the frames endwise of the support, keys on the support, and cooperating grooves in the frames for effecting a sidewise movement of the frames. 95
15. In a paper making machine, the combination of the making wire, a pair of sliding frames, suction boxes supported by the frames, an operating shaft, connections from the shaft for sliding the frames in opposite directions, cooperating keys and grooves for effecting a sidewise movement of the frames, a prime mover, and means for reversing the prime mover. 100
16. In a paper making machine, the combination of the making wire, a pair of sliding frames, suction boxes supported by the frames, an operating shaft, connections from the shaft for sliding the frames in opposite directions, cooperating keys and grooves for effecting a sidewise movement of the frames, a reversing motor, and a reversing switch operated from one of the frames. 105
17. In a paper making machine, the combination of the making wire, a pair of sliding frames, suction boxes supported by the frames, an operating shaft, a right hand screw rod connected with one of the frames, a left hand screw rod connected with the other frame, connections from the shaft to the rod, cooperating keys and grooves for effecting a sidewise movement of the frames, a motor, and means for reversing the motor. 110
18. In a paper making machine, the combination of the making wire, a pair of sliding frames, plates supported by the frames, slots in the plates, suction boxes pivotally supported by the slots, an operating shaft, connections from the shaft for sliding the frames in opposite directions, and means for driving the shaft in opposite directions. 115
19. In a paper making machine, the combination of the making wire, a pair of sliding frames, plates supported by the frames, slots in the plates, suction boxes pivotally supported by the plates, a support on which the frames slide, cooperating keys and grooves in the support and frames, an operating shaft, connections from the shaft to the frames, and means for driving the shaft in opposite directions. 120

In witness whereof, we have hereunto set our hands.

CHARLES W. VALENTINE.
ALFRED F. HELIN.
